SLIDING MAILBOX APPARATUS

Anthony H. Kaschak, Bristol, Conn.

Application August 4, 1950, Serial No. 177,619

1 Claim. (Cl. 248—128)

1

This invention relates to mail boxes, and more particularly to mail boxes for use on rural delivery routes.

It is common knowledge that R. F. D. mail routes are usually on unpaved roads that are often obstructed along the sides by snow drifts in the winter, and mud ditches in the spring. Because of this, the ordinary mail box, fixed on a post at the edge of the road, is often inaccessible, both to the mail delivery man leaning from his delivery vehicle, and the householder in receiving the mail.

It is accordingly one object of this invention to provide a mail box having a rod fixed thereto which is slidably mounted on a fixed support so that said box may be pulled forward to a position accessible to the mail carrier by means of a hook which may be detachably engaged in an eye on said rod, thus facilitating a mail delivery under conditions where it would otherwise be necessary for the mail man to leave his vehicle.

A further object is to provide a mounting means of the above nature which may be used by the householder during adverse road conditions created by changes in the weather.

A further object is to provide a mounting means of the above nature which may be easily and inexpensively installed upon a mail box.

A further object is to provide a mail box of the above nature which will allow the mail man the free use of both hands for sorting and distributing and receiving mail when the box is in the fully extended position.

A further object of the invention is to enable the mail man or householder to return the box to its retracted position by the use of an S-shaped hook without re-engaging the hook in the eye on the sliding rod.

A further object is to provide a visual means of indicating that mail has been delivered, which may be accomplished by leaving the box in a partly retracted position.

With these and other objects in view, there has been illustrated on the accompanying drawing one form in which the invention may conveniently be embodied in practice.

In the drawing,

Fig. 1 is a perspective view of the mail box in its fully retracted position.

Fig. 2 is a perspective view of the mail box in its fully extended position.

Referring now to the drawing, in which like reference numerals denote corresponding parts throughout the several views, the numeral 10 indicates a vertical post mounted in the ground 11,

2

said post having a pair of spaced apertured upstanding plates 12 and 13 secured at the top end thereof. The forward plate 12 is raised slightly higher than the rear plate 13, so that a sliding rod 14 loosely fitted within apertures 15 in said plates 12, 13 and attached to a mail box 16 will remain level when pulled forward by a hook 21. The mail box 16 is rigidly fastened to the rod 14 by means of two T-shaped brackets 17 having curved ears 17a which are, in turn, secured to the mail box by bolts or other suitable means. The rod 14 has a removable headed stop screw 18 at its rear end, and a closed eye 19 at the forward end. The stop screw 18 is made removable to permit the rod 14 to be inserted through the apertures 15 of the plates 12 and 13.

Provision is also made of a rod 21 having an S-shaped hook 20 at its rear end for engaging the eye 19 of the sliding rod 14. The front end of the rod 21 has a handle 22 for facilitating the gripping of same by the operator.

Operation

When encumbrances, such as snow or mud, are encountered during the delivery of mail, it is only necessary for the mail man to drive his vehicle reasonably close to the mail box, then insert the S-shaped hook 20 of the rod 21 in the eye 19 of the rod 14, and pull the mail box 16 from the rear position shown in Fig. 1, to the forward position shown in Fig. 2 using the base loop of said hook. The hook 20 may be allowed to remain engaged with eye 19 until mail is inserted into or removed from the box 16, which may then easily be returned by the rod 21 to its fully retracted position (Fig. 1) using the free loop of said hook, or it may be only partly returned to thereby serve as a signal that the mail has been delivered. Alternately, the mail box may be left at a partially extended position so as to be readily accessible by either the mail delivery man or the householder for the duration of the obstruction at the edge of the road.

One advantage of this invention is that the parts of the attachment may be sold as a kit ready to be assembled to any standard mail box and supporting post.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes

all the modifications and embodiments coming within the scope of the following claim.

Having thus fully described the invention, what is claimed as new, and for which it is desired to secure Letters Patent, is:

A mail box having a pair of eye-brackets attached upon the top thereof, an elongated flexible horizontal rod fitted within said eye-brackets and secured thereto, a removable stop member at one end of said rod, an upright support post having a pair of apertured strips extending above said post on opposite sides thereof, and within which said rod is slidably guided, one strip serving as an abutment to limit the forward movement of said stop member, the other strip extending above the front strip so as to cause said rod to remain level under the weight of said box when pulled forwardly, a closed eye on the forward end of

said rod, and a manually-operated handle rod having an S-shaped hook at its extremity detachably insertable in said eye to facilitate pulling said rod outwardly with respect to said post using the base loop of said hook and pushing it inwardly with respect thereto using the free loop of said hook.

ANTHONY H. KASCHAK.
